PREPARATION OF PENTAERYTHRITOL

Joseph A. Wyler, Allentown, Pa., assignor to
Trojan Powder Company, Allentown, Pa.No Drawing. Application April 27, 1939,
Serial No. 270,340

4 Claims. (Cl. 260—635)

This invention relates to a process for the preparation of pentaerythritol and more particularly to a process for the alkaline condensation of formaldehyde and acetaldehyde to pentaerythritol through the use of a combination of catalysts.

In my co-pending application S. N. 200,683 is disclosed the process for the preparation of pentaerythritol from formaldehyde and acetaldehyde through the use of oxalates of metals of the 1st long period of Mendelejeff's Periodic System having atomic weights between 52 and 63.6.

I have now discovered that if certain agents be used in combination with the above mentioned catalysts that further important improvements in the process result.

It is well known that pentaerythritol is formed by the condensation of four molecules of formaldehyde with one molecule of acetaldehyde in the presence of such alkalies as NaOH, KOH, Ca(OH)₂, or Ba(OH)₂, and although many such processes are described in the literature, the yields are usually low—approximately 60% of theory. In addition to the low yields, further unfavorable factors in these processes are the formation of a relatively large amount of a dark colored, resinous syrup and the length of time required to complete the reaction.

It is an object of my invention to increase the yield of pentaerythritol received from a given amount of aldehydes. A further object is to prevent the formation of colored products during the condensation of the CH₂O and CH₃CHO. A still further object is to shorten the time required to complete this condensation. Other and further objects will become apparent upon a perusal of this specification.

In general, the commercial condensation of CH₂O and CH₃CHO is based upon the use of 4 to 5 molecules of formaldehyde for each molecule of acetaldehyde in alkaline media, at temperatures not exceeding 50° C., and in such a volume of water as to provide a solution to contain less than 20% of aldehydes at the beginning of the reaction.

Although the general reaction for the formation of pentaerythritol is as follows:

the pentaerythritol is generally believed to be the result of the following reactions:

1. $2\text{CH}_3\text{CHO} + 6\text{CH}_2\text{O} = 2(\text{CH}_2\text{OH})_3\text{C}\cdot\text{CHO}$
MacLeod's aldehyde
2. $2\text{CH}_2\text{O} + \text{Ca}(\text{OH})_2 = \text{Ca}(\text{OOC})_2 + 2\text{H}_2\text{O}$
3. $2(\text{CH}_2\text{OH})_3\text{C}\cdot\text{CHO} + 4\text{H} = 2\text{C}(\text{CH}_2\text{OH})_4$
Pentaerythritol

In addition to these reactions others, producing sugary, syrupy products also take place and

it is evident that the more perfect the balance between reactions 1 and 2, the greater the yield of pentaerythritol and the less the yield of syrupy products.

In the above mentioned application I have disclosed the use of oxalates of Fe, Co, Cr, Mn, Ni, and Cu individually or in admixture, as agents for effecting a more complete balancing of the above reactions and in the present application I am disclosing the use of Cu₂O, Cu or Pt or mixtures of these in combination with any of the above oxalates or mixtures thereof.

I have discovered for instance, that a mixture of Cu₂O+CuC₂O₄, or Cu+CuC₂O₄ constitutes a far superior catalyst than Cu₂O or CuC₂O₄ alone. Similarly Cu₂O+NiC₂O₄, or Cu+NiC₂O₄, or Pt+NiC₂O₄ constitutes a catalyst superior to the NiC₂O₄, etc. In other words, the addition of the Cu₂O, Cu or Pt has the effect of causing a more thorough hydrogenation of MacLeod's aldehyde and it also shortens the time required to do this, other conditions being uniform.

The following examples in which all parts given are by weight, illustrate my invention.

Example #1

396 parts of 30.34% formaldehyde and 79.5 parts of 52.8% commercial acetaldehyde are mixed with 966 parts of water in a suitable container provided with a stirrer. To this is slowly added, with stirring, a mixture of 40 parts of CaO and 100 parts of water. This slurry is added over a period of three to five hours and the reaction mixture is kept at approximately 20° to 30° C. throughout the period of addition.

Just before the beginning of the addition of the lime slurry, 0.25 part of finely powdered copper oxalate is added to the mixture of aldehydes, and when about half the lime is in, 1 part of Cu₂O is added. After all the lime is in, the stirring is continued, at 20° to 30° C., until an iodine titration indicates less than, say, 0.10% of total aldehydes, calculated to CH₂O. The time to arrive at this point varies somewhat but it is usually not over 6½ to 7 hours.

The reaction mixture, at completion, is treated with slightly less sulphuric acid than is theoretically equivalent to the lime used. This precipitates most of the lime as calcium sulfate. In order to precipitate all of the calcium out of solution, a small amount of oxalic acid is added in the form of a water solution and the mixture stirred for an hour or more, when it is filtered. The filtrate is evaporated and the pentaerythritol recovered by crystallization.

If this same run had been made without the addition of the Cu₂O the time required for the reaction would have been about 20 hours and the yield of pentaerythritol about 80% of theory. (Based on either the acetaldehyde or on the

formaldehyde.) In the present example the yield is 90% to 92% of theory. In calculating the yields of pentaerythritol, any dipentaerythritol which forms is considered as pentaerythritol.

5

Example #2

1 part of freshly reduced Cu is used in the condensation reaction mixture in place of the Cu₂O mentioned in Example #1, and the process carried out essentially as there described.

10

Example #3

0.03 part freshly prepared platinum black is used in the condensation reaction mixture in place of the Cu₂O mentioned in Example #1, except that in this case, I prefer to add the platinum somewhat later in the condensation process, that is, at the stage where the acetaldehyde has practically all been converted to MacLeod's aldehyde. This is indicated when about 75% of the total original aldehydic content (as indicated by iodine titration) of the mixture has been consumed. The platinum exerts a somewhat more vigorous hydrogenation action than does Cu and, if added too soon, causes the reduction of CH₃CHO to CH₃CH₂OH and thus tends to diminish the yield of pentaerythritol. The best stage at which to add the Pt depends upon such conditions as concentration of aldehydes to start with, base used in the condensation, temperature and the amount of catalyst added. Yields of pentaerythritol of over 90% of theory are obtainable.

In these examples only the preferred conditions are given. I may start out with stronger concentrations of aldehydes; use a lesser or greater amount of the metal oxalate, cuprous oxide, copper or platinum; use any water soluble fixed alkali as Ba(OH)₂, Sr(OH)₂, NaOH, KOH, K₂CO₃, Na₂CO₃, (CH₃)₄N(OH), (C₂H₅)₄N(OH), etc.; vary the temperature at which the reaction is carried out, the rate of addition of the alkali or the amount of alkali; or, in short, I may use such operative conditions or details as would occur to a workman skilled in this art, without departing from the essence of this invention.

45 I claim:

1. The process for the preparation of penta-

rythritol comprising the condensation in aqueous media of formaldehyde and acetaldehyde to pentaerythritol in the presence of a fixed alkali, an oxalate of a metal of the 1st long period of Mendelejeff's Periodic System, having an atomic weight between 52 and 63.6, and a member of the group consisting of finely divided cuprous oxide and copper.

5

2. The process for the preparation of pentaerythritol comprising the condensation in aqueous media of formaldehyde and acetaldehyde to pentaerythritol in the presence of a fixed alkali, an oxalate of a metal of the 1st long period of Mendelejeff's Periodic System, having an atomic weight between 52 and 63.6, and a member of the group consisting of finely divided cuprous oxide and copper, the molecular ratio of the formaldehyde to acetaldehyde being approximately four to one and the total aldehyde content of the solution being less than 20% by weight.

10

3. The process for the preparation of pentaerythritol comprising the condensation in aqueous media of formaldehyde and acetaldehyde to pentaerythritol in the presence of calcium hydroxide, copper oxalate and a member of the group consisting of finely divided cuprous oxide and copper, the molecular ratio of the formaldehyde to the acetaldehyde being approximately four to one and the total aldehyde content of the solution being less than 20% by weight.

15

4. The process for the preparation of pentaerythritol comprising the condensation in aqueous media of formaldehyde and acetaldehyde to pentaerythritol in the presence of calcium hydroxide, copper oxalate and a member of the group consisting of finely divided cuprous oxide and copper, the molecular ratio of the formaldehyde to the acetaldehyde being approximately four to one and the total aldehyde content of the solution being less than 20% by weight, the proportion, by weight, of the copper oxalate to formaldehyde (100%) being approximately 0.25 to 119, that of the cuprous oxide being about one to 119, that of the copper being about one to 119.
